UNITED STATES PATENT OFFICE.

MERLE A. VARNEY, OF CHICAGO, ILLINOIS.

FUEL-CONTROLLING MECHANISM FOR INTERNAL-COMBUSTION ENGINES.

1,406,591.

Specification of Letters Patent. Patented Feb. 14, 1922.

Application filed April 21, 1917. Serial No. 163,665.

To all whom it may concern:

Be it known that I, MERLE A. VARNEY, a citizen of the United States, residing at Chicago, in the county of Cook and State 5 of Illinois, have invented new and useful Improvements in Fuel-Controlling Mechanism for Internal-Combustion Engines, of which the following is a full, clear, concise, and exact description, reference being had to 10 the accompanying drawing, forming a part of this specification.

My invention relates to fuel-controlling mechanism for internal combustion engines and has to do more particularly with means 15 for automatically switching from one fuel to another, such as from gasoline to kerosene, an object of my invention being to provide mechanism of this character which is automatic in its control and positive in its operation.

In the ordinary combustion engine using electrical ignition it has been found that in starting, the heavier liquid fuels, such as kerosene, cannot be used, although after the 25 engine and manifold have been heated up to the proper temperature such fuel may be used by passing it through a heated chamber so that it may be readily vaporized. Various means have been provided for starting the engine on a light, volatile, combustible liquid, such as gasoline, as fuel, until the parts have been sufficiently heated, at which time the gasoline is shut off and kerosene supplied.

One of the features of my invention is the provision of a thermostatically-controlled electromagnetic device which is adapted to switch from gasoline to kerosene, and vice versa, as the temperature in the 30 heating chamber around the kerosene intake manifold varies. That is, in starting the engine when it is cold the electromagnet is in such position that the kerosene is shut off and the gasoline on. The engine is then 40 started in the usual manner, and as soon as the heating chamber around the kerosene intake manifold becomes heated to a predetermined temperature, the thermostat therein operates, closing a circuit for the electromagnetic device which operates a valve to close the gasoline supply and open the kerosene supply. If the temperature in the heating chamber drops to a predetermined point, for instance, when the engine is 45 stopped, the thermostat arm will move to its alternate position, again affecting the elec-

tromagnetic device which operates to close the kerosene intake and open the gasoline intake. It will thus be seen that the valve automatically operates to switch from one 60 fuel to another, according to the temperature of the heating chamber.

For a better understanding of my invention, reference is to be had to the accompanying drawings, in which like reference 65 characters indicate like parts, and in which—

Figure 1 is a side elevation of a well-known type of automobile engine having my control apparatus operating in connection 70 therewith; and

Fig. 2 diagrammatically illustrates the electromagnetic mechanism and circuit for controlling the valves.

Referring now more particularly to the 75 preferred form of my invention as shown herein, it comprises the usual exhaust manifold 1, an intake manifold 2, a gasoline carbureter 3, a kerosene carbureter 4, the usual heating connections 5 and 6 extending from 80 the exhaust manifold to the carburetors, and kerosene and gasoline supply-pipes 7, 8, respectively, the kerosene pipe 8 being wound around the exhaust pipe, if desired, so as to warm the kerosene before entering 85 the carburetor. These parts are, of course, used in connection with the engine. The downwardly-extending portion 9 of the intake manifold is constructed at the bottom so as to take a gasoline connecting-pipe 10 90 and kerosene connecting pipe 11, these pipes being fitted tightly through machined openings extending into the chamber 9. A heating chamber 12 is provided for the intake manifold, preferably surrounding the kero- 95 sene intake pipe 11 so as to heat the same and effect a vaporization of the kerosene. The pipe 11 has longitudinally extending plates 23 constructed so as not to impede the flow of the fluid, the pipe and plates 100 acting as a heating element to assist in more readily vaporizing the heavier fluid, as kerosene. This heating chamber 12 is connected by means of a pipe 13 of suitable dimensions and extending from the exhaust manifold 105 1 to the chamber 12 the exhaust passing downwardly through the chamber 12 and out of the exhaust-pipe 14. The lower end of the heating chamber 12 is preferably closed by a cover 15 suitably secured there- 110 to. The ends of the intake pipes 10, 11 are machined and act as seats for the valve 16,

which valve is supported upon a shaft 17 carrying a slotted arm 18 upon its outer end. Thus, as the arm 18 is reciprocated, the valve 16 operates to open and close the 5 kerosene and gasoline intakes. In Fig. 1, the kerosene side is closed by the valve 16, the dotted lines of 16 indicating its position when the gasoline side is closed.

For the purpose of controlling the valve 10 16, I preferably provide an electromagnetic device the circuit of which is controlled by a thermostat 19 located within the heating chamber 12.

In order to maintain the temperature of 15 this heating chamber 12 within predetermined limits, so that it will not become too hot, I provide a second thermostat 20 which is adapted to control an electromagnetic device which operates a valve 21 located within 20 the exhaust connection 13; that is, if the chamber 12 reaches a predetermined high temperature the thermostat 20 operates and affects the electromagnet which controls the valve 21 within the pipe 13, thereby closing 25 this valve 21 sufficiently to maintain this chamber below the predetermined high temperature. If the valve 21 is partly closed and the temperature of the chamber 12 is reduced to the lower predetermined limit, 30 the thermostat 20 closes its alternate contact and again actuates the electromagnetic device to open the valve 21. Thus, the temperature of the chamber 12 is maintained within predetermined limits.

35 Referring now to the electromagnetic control mechanism shown in Fig. 2, it includes the thermostat 19, and electromagnetic mechanism A. This includes suitable electromagnets, an electromagnet 26 operating 40 to open the kerosene intake and close the gasoline intake, and electromagnet 27 operating to open the gasoline intake and close the kerosene intake. An armature 28 is pivotally supported between the polar extensions of the electromagnets and carries a pin 29 which extends into the slot 30 of the valve arm 18. Thus, as the armature 28 is moved back and forth, the valve arm 18 and valve 16 are operated accordingly.

50 In order to hold the valve 16 in either position, I preferably provide mechanical locking means and circuit-interrupting means, so that when the armature is attracted in either direction the circuit of the 55 operating magnet is interrupted and the valve locked in its last-operated position. Thus a saving of current is effected, as the magnet has its circuit interrupted except during the short period of operation.

60 As shown in Fig. 2, the mechanism is in the position assumed thereby when the motor and heating elements 11, 23, 12 are cold; that is, we might say when starting, with the valve 16 in its full line position and the 65 gasoline intake open and the kerosene intake

closed, as shown in Fig. 1. To lock the armature 28, auxiliary armatures 31 and 32 are provided for the electromagnets. These armatures coöperate with the pin 33 carried by the armature 28, this pin extending across 70 the edge of the free end 34 of armature 31, as shown in Fig. 2, whereby the armature 28 is locked. Before this armature can be attracted by the magnet 26, auxiliary armature 31 is attracted, thereby moving the free end 34 out of the path of the pin 33, whereby armature 28 may be attracted to the magnet 26. During this movement of armature 28 the pin 33 rides upon the under side of arm 35 of the auxiliary armature 32 until the armature 28 is in the position indicated by the dotted line, at which point the free end 35 drops down behind the pin 33 into its dotted line position, locking itself and interrupting the contact 36. This, of course, 80 interrupts the circuit of magnet 26, so that current is not consumed until a further operation of the magnet is necessary. It will be noted that contact 37 of electromagnet 27 is open, while armature 28 is in its left-hand position, thus maintaining the circuit of magnet 27 interrupted. It will be noted that the armatures 31, 32 are normally grounded, while the ungrounded terminal of battery 38 is connected to the movable arm 39 of the 90 thermostat, this arm being adapted to move between contacts 40, 41 in order to close the circuit through magnets 26, 27.

Operation: Referring now more in detail to the operation of my invention with the 100 apparatus in the position assumed thereby when the engine is cold, as for instance in starting, and as illustrated in the drawings, the kerosene carbureter 4 is shut off but the gasoline carbureter 3 is connected, due to 105 the position of valve 16. The valve magnets are as shown in Fig. 2. The engine is now started in the usual manner, being provided with fuel through the gasoline carbureter 3, and as soon as the heating chamber 12 reaches a predetermined temperature the 110 thermostat arm 39 closes contact 40 and establishes a circuit from battery 38 through contact 40, magnet 26, contact 36 and armature 32 to ground. Magnet 26 therefore 115 first attracts auxiliary armature 31 moving end 34 clear of pin 33 after which armature 28 is attracted to magnet 26. As the armature 28 moves into its right-hand or dotted line position the pin 33 carried thereby permits auxiliary armature 32 to drop at its free end 35 into the dotted-line position, whereby the contact 36 is opened, interrupting the circuit of magnet 26, while the free end 35 of armature 31 locks armature 28 in 125 its attracted position. The gasoline intake 10 is thus closed and the kerosene intake 11 opened. The engine now continues to run on the kerosene supply as long as the heating chamber 12 stays above a predetermined 130

minimum temperature. Should this temperature drop below the predetermined point, the thermostat arm 39 moves to its alternate contact 41, closing a circuit 5 through magnet 27, whereby auxiliary armature 32 is first attracted to unlock the armature 28, after which armature 28 is attracted toward the left, operating valve 16 to open the gasoline intake 10 and close the kerosene 10 intake 11.

It will thus be apparent that by means of the control provided herein the switching from gasoline to kerosene, and vice versa, is entirely automatic and manual manipulation 15 of the apparatus is unnecessary.

In order to prevent the heating chamber 12 from becoming too hot, I provide a second thermostat 20, which controls the valve 21 within the heating chamber supply-pipe 20 13, this valve 21 being controlled by electromagnetic mechanism similar to A. The armature 28 is connected to an arm 118 so that as the armature is reciprocated, the valve 21 is operated. The thermostat 20 is 25 preferably adjusted so that its contact 41 is maintained closed as long as chamber 12 is below a predetermined limit of temperature. As soon as the temperature of this chamber 12 rises above the predetermined 30 point, its contact 40 is closed to operate electromagnet 26, which first operates the auxiliary armature 31 and thereafter armature 28 to actuate arm 118 and thus partly close valve 21. Should the temperature of 35 chamber 12 again drop below the predetermined point, thermostat 20 operates to close its contact 41 and thereby actuate electromagnet 27 to again open the valve 21. Thus, the temperature of chamber 12 is 40 automatically maintained between predetermined limits.

While I have not shown the electromagnetic apparatus A mounted in Fig. 1, it is 45 to be understood that it is suitably mounted to coöperate with the valve/arms 18 and 118.

For the purpose of illustrating my invention I have chosen a preferred arrangement, but it is to be understood that I contemplate applying my invention in other ways 50 than that shown. Various changes and modifications will readily occur to those skilled in the art, and therefore I do not desire to be limited to the exact structure shown and described, but aim to cover all 55 that which comes within the spirit and scope of the appended claims.

What I claim as new and desire to secure by Letters Patent is:—

1. Fuel controlling mechanism for 60 internal combustion engines comprising an intake manifold, two fuel supply intakes therefor, one only of said intakes being provided with a heating chamber, a thermostat within said heating chamber, and an electromagnetically operated valve for switching from

one intake to another controlled by said thermostat.

2. Fuel controlling mechanism for internal combustion engines comprising an intake manifold, two fuel supply intakes therefor, a heating chamber for one intake having a thermostat therein, the other of said intakes having no heating chamber, means for heating said chamber by the engine exhaust and an electromagnetically operated valve 75 for switching from one intake to another controlled by said thermostat.

3. Fuel controlling mechanism for internal combustion engines comprising an intake manifold, two fuel supply intakes therefor, a valve for connecting said manifold with either supply intake, a heating chamber for one supply intake, having a thermostat therein for controlling the heat in said chamber, the other intake passing around 80 said heating chamber, a pair of electromagnets alternatively operable to actuate said valve, and connections from said thermostat for controlling said electromagnets.

4. Fuel controlling mechanism for 90 internal combustion engines comprising an intake manifold, two fuel supply intakes therefor, a valve for connecting said manifold with either supply intake, a heating chamber for only one supply intake, a thermostat 95 in said chamber having contacts alternately closed upon said chamber reaching predetermined upper and lower temperatures, and electromagnetic means controlled by said thermostat for operating said valve to connect one or other supply intake according to the temperature of said heating chamber.

5. Fuel controlling mechanism for 100 internal combustion engines comprising an intake manifold, two fuel supply intakes therefor, a heating chamber for only one supply intake, a thermostat in said chamber for regulating the temperature in said chamber having contacts alternately closed upon said chamber reaching predetermined upper and 105 lower temperatures, a valve for switching from one intake to another, and means controlled by said thermostat contacts for automatically operating said valve.

6. Fuel controlling mechanism for 110 internal combustion engines comprising an intake manifold, two fuel supply intakes therefor, a fuel heating chamber for one intake having a thermostat therein, the other of said intakes avoiding said heating chamber, means for heating said chamber by the engine exhaust, the other of said intakes having no fuel heating means, an electromagnetically operated valve for switching from one intake to another controlled by said thermostat, and automatic means for regulating the temperature of the heating chamber.

7. Fuel controlling mechanism for 120 internal combustion engines comprising an in- 130

- take manifold, two fuel supply intakes therefor, a valve for connecting said manifold with either supply intake, a fuel heating chamber for one supply intake, means for 5 heating said chamber by the engine exhaust, a thermostat in said chamber having contacts alternately closed upon said chamber reaching predetermined upper and lower temperatures, electromagnetic means 10 controlled by said thermostat for operating said valve to connect one or the other supply intake according to the temperature of said heating chamber, and means for regulating the temperature of the heating chamber.
- 15 8. Fuel controlling mechanism for internal combustion engines comprising an intake manifold, two fuel supply intakes therefor, a fuel heating chamber having a thermostat therein, means for conducting one only 20 of the fuel supply intakes through the heating chamber so as to be heated thereby, and an electromagnetically operated valve for switching from one intake to another controlled by said thermostat.
- 25 9. Fuel controlling mechanism for internal combustion engines comprising an intake manifold, two fuel supply intakes therefor, a fuel heating chamber, a conducting chamber extending through the heating 30 chamber for connecting one only of said fuel supply intakes with the manifold, a thermostat in said fuel heating chamber having contacts alternately closed upon said heating chamber reaching predetermined upper 35 and lower temperatures, a valve for switching from one intake to another, and means controlled by said thermostat for automatically operating said valves.
- 40 10. Fuel controlling mechanism for internal combustion engines comprising an intake manifold, two fuel supply intakes there- for, a heating chamber surrounding one only of said intakes a valve adapted to close either of said intakes, a thermostat adapted to control the movements of said valve and a 5 second thermostat adapted to regulate the temperature of said chamber.
11. In a device of the character described, thermostatically controlled valve mechanism comprising a thermostat having a plurality 50 of contacts, an electromagnet controlled by each of said contacts, a valve operating armature pivotally mounted between and adapted to be attracted by either of said electromagnets, means for locking said armature in either of its operative positions, and automatic means for interrupting the circuit of either of said electromagnets after said electromagnet has attracted said armature.
12. In a device of the character described, 60 thermostatically controlled valve mechanism comprising a thermostat having a plurality of contacts, an electromagnet controlled by each of said contacts, a valve operating armature pivotally mounted between and 65 adapted to be attracted by either of said electromagnets, means for locking said armature in either of its operative positions comprising pivoted locking armatures, a lug on said first mentioned armature adapted to co- 70 operate with said locking armatures and springs urging said locking armatures to locking position, said locking armatures being moved to unlocking position by said electromagnets, and means for interrupting the 75 circuit of either of said electromagnets after said electromagnet has attracted said armature.

In witness whereof, I have hereunto subscribed my name.

MERLE A. VARNEY.
